(57) **CLAIM**

The ornamental design for a combined door anchor attachment and exercise equipment holder, as shown and described.

DESCRIPTION

FIG. 1 is a front perspective view of a combined door anchor attachment and exercise equipment holder, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the combined door anchor attachment and exercise equipment holder, shown in a condition of use thereof.

The broken line showing of FIG. 8 is for the purpose of illustrating environmental structure (for example, a closed door) and forms no part of the claimed design.

The combined door anchor attachment and exercise equipment holder is shown with symbolic breaks in its length in FIG. 1. The appearance of any portion of the article between the break lines forms no part of the claimed design.
